INVENTOR
Herman Notke
BY Chappell & Bear
ATTORNEY

UNITED STATES PATENT OFFICE.

HERMAN NOTTKE, OF BATTLE CREEK, MICHIGAN.

GRADE CROSSING.

Application filed October 7, 1926. Serial No. 140,088.

The objects of this invention are,

First, to provide in a grade crossing for railroads an improved metallic construction in which the plate fastening means are 5 easy of manipulation and concealed and protected from wear.

Second, to provide such a knock-down construction with interchangeable floor plates of convenient size.

10 Third, to provide improved means of retaining the approach plates in place.

Objects pertaining to details will appear from the detailed description to follow.

I accomplish the objects of the invention 15 by the devices and means described in the following specification. The invention is defined in the claims.

20 A structure which is a preferred embodiment of my invention is illustrated in the accompanying drawing, forming part of this application, in which:

25 Fig. 1 is a detail plan view in broken section, certain parts being cross sectioned on line 1—1 of Figs. 2 and 4, showing a railway crossing embodying the features of my invention.

Fig. 2 is a longitudinal detail sectional view taken on line 2—2 of Fig. 1.

30 Fig. 3 is a transverse detail sectional view on line 3—3 of Figs. 1 and 2.

Fig. 4 is an enlarged detail sectional view on line 4—4 of Fig. 1, showing details of the plates of the approach and their support.

35 Fig. 5 is a similar enlarged detail sectional view taken on line 5—5 of Fig. 1, showing details of the spacer block in position.

Fig. 6 is a detail section on line 4—4 of Fig. 1, of the frame of the approach, the floor plate being omitted.

40 Fig. 7 is a detail perspective view of one of the spacer blocks 11.

Fig. 8 is an inverted detail perspective view of one of the main floor plates, showing the integral attaching lug.

45 Fig. 9 is an enlarged detail of insulated joint for cross arms.

The parts will be identified by their numerals of reference, which are the same in all the views.

50 1, 1 are the rails of the railroad track.

2, 2 are the usual railroad ties. 3 are the spikes for holding the rails in place. 4 is the approach frame. 5 are the end and

cross arms of the approach frame, of a notched form at their inner ends 51 to fit 55 the base, web and head of the rail. 6 are the attaching bolts with nuts 61 preferably used inside the rails for clamping the approach frame in place against the outside of the rails, as seen in Fig. 3. 7 are the floor plates 60 for the approach, with downwardly-disposed lugs 71 to receive attaching bolts 72 disposed therethrough and through the cross arms 5 (see particularly cross section in Fig. 1). These plates are bolted in place to 65 the cross arms before the approaches are secured by their attaching bolts 6.

8, 8 are the rail end support of the central platform, secured by suitable spikes or bolts 81 to the ties. These ends are rabbeted or 70 flanged at 82 to retain the floor plates. 9, 9 are the intermediate floor support rails parallel with the ends 8. 10 is a supporting frame between the supports, with sides 101 parallel to and spaced from the rails, and 75 having intermediate cross bars 102 forming a supporting grid for the floor plates. The ends of the sides 101 conform to the flanges of the support rails and are retained in place thereby. Spacer blocks 11 keep the platform in central position. The floor plates 12 are interchangeable and are disposed on the frame and are provided with perforated lugs 121. They are secured by rods 122 disposed through perforations in the frame 80 sides and the lugs. The rods are bent at one end. The cross bars 8 and 102 are divided at the center and an insulated joint (see Fig. 9) is interposed, the same being also 85 insulated from the floor plate above. 90

Having thus described my invention, what I claim as new and desire to secure by Letters Patent is:

1. In a railway crossing, the combination 95 of flanged rail supports, a grid-like frame between the said supports, interchangeable floor plates disposed on said frame and provided with attaching lugs, a cross rod through the attaching lugs and frame, retained in place by the rails of the track, and 100 spacer blocks for the said grid frame to hold it in spaced relation to the track, coacting as specified.

2. In a railway crossing, a support comprising a framework, bolts therethrough to 105 attach the same to the web of the rail, de-

tachable floor plates with perforated lugs, and bolts therethrough for attachment to the frame.

3. A railway crossing comprising a central platform, sectional frames for the said platform, supporting end rails therefor, cross bolts therethrough disposed between the said rails, an approach comprising an auxil-

iary frame with cross bars conformed to the rails, bolts through the same to the said rails, and interchangeable floor boards with suitable lugs for attaching to the said frame, as specified. 10

In witness whereof I have hereunto set my hand.

HERMAN NOTTKE.
